UNITED STATES PATENT OFFICE.

RALPH C. SEYMOUR, OF LARCHMONT, NEW YORK, ASSIGNOR TO GOSS PRINTING PRESS COMPANY, A CORPORATION OF ILLINOIS.

PRINTING-PRESS.

1,305,568.

Specification of Letters Patent. Patented June 3, 1919.

Application filed July 16, 1915. Serial No. 40,244.

To all whom it may concern:

Be it known that I, RALPH C. SEYMOUR, a citizen of the United States, residing at Larchmont, in the county of Westchester 5 and State of New York, have invented certain new and useful Improvements in Printing-Presses, of which the following is a specification.

The invention relates to folding and 10 printing machines and in certain aspects thereof more especially to rotary folding and printing machines for producing a large variety of sizes of printed and folded products from sheets of relatively numerous and 15 various sizes.

The objects and advantages of the invention will in part be set forth hereinafter and in part will be obvious herefrom, such 20 objects and advantages being attained by the means and instrumentalities set forth in the appended claims.

The invention consists in the novel parts, constructions, arrangements, combination and improvements herein shown and 25 described.

The accompanying drawings, referred to herein and constituting a part hereof illustrate one embodiment of the invention, and together with the description serve to 30 explain the principles thereof.

Of the drawings:

Figure 1 is a view, partly diagrammatic of a machine constructed in accordance with the principles of the invention and showing 35 the machine printing upon sheets which are afterward folded;

Fig. 2 is a view generally similar to Fig. 1 but shows the machine printing on a web, the web being thereafter cut and folded;

Fig. 3 is a view on an enlarged scale of 40 the left-hand end of Fig. 1, showing the machine folding sheets of relatively large size; and

Fig. 4 is a view similar to Fig. 3 but showing 45 the machine folding sheets of relatively small size.

Referring to the accompanying drawings, illustrating by way of example one embodiment of the invention, means are provided 50 for varying the speed of the web and cutting means relatively to a given speed of the printing means, and also in accordance with certain aspects of the invention for varying the speed of the web and of the cutting means relatively to each other and rela-

tively to a given speed of the printing means to get products of different sizes when the machine is printing upon cut sheets. By such changes in the relative speed of the web of the cutters and of the printing 60 mechanism, a much greater variety of sizes of product may be secured than could be secured by mere adjustment of the mechanism, and the desirable results may also be effected of running the folding mechanism 65 at full capacity with any size product turned out.

In accordance with many features of the invention, and as exemplified in the drawings, the invention is embodied in a rotary 70 machine fed from a web roll. A web roll 1 is shown and in connection therewith a variable feed. As embodied, the web roll 1 rests upon feeding rolls 2 and 3 which are of variable speed thereby giving the desired 75 changes in the lineal speed or feeding of the web. In accordance with one feature of the invention, it is contemplated to provide a full speed and a half speed of the web with respect to the speed of the printing cylinders, and also variations in the speed of the web from such full speed and such half speed. Suitable devices for effecting this may be applied to the web roll, feed rollers 80 2 and 3, such as changeable gears to give the 85 full speed and half speed, and a variable drive, such as cone pulleys or a variable disk drive or other suitable means for the lesser variations in the feeding speed of the web. Thus the web may be fed off at full speed, or 90 slightly slower than full speed or at half speed or somewhat slower or faster than half speed.

Suitable guiding and feeding rolls for the web are provided such as rolls 10, 11 and 12 95 and 13 and 14 which direct the web into the cutting devices located ahead of or in front of the printing cylinders. Certain of the directing and feeding rolls for the web, such as the rolls 11 and 14 may have adjustable 100 spring tension in a well-known manner.

The invention in some of its aspects includes cutting devices variable in their frequency of cutting with respect to the rotations or frequency of printing of the printing mechanism, and operating to cut the web with various changes as indicated in the speed thereof. In accordance with certain features of the invention, the foregoing 105 are embodied and applied to rotary cutters. 110

In the embodied form, coöperating cutters are shown on each side of the web, one cutting mechanism being mounted on shaft 18, from which, extend radially shear blade holders 19 and 20 carrying respectively removable shear blades 21 and 22. On the opposite side of the web path is a rotatable shaft 23 having diametrically disposed shear blade holders 24 and 25 likewise carrying respectively removable shear blades 26 and 27.

Suitable driving or rotating means for the cutting mechanism are provided, and for the purpose of giving or securing a change in timing of the cutters relatively to the web, the blade holders may be angularly adjustable relatively to the shafts 18 and 23, or the shafts 18 and 23 may be angularly adjustable relatively to their driving gears. The cutters may be run at the same speed as the printing cylinders or at half their speed by suitable means, such as changeable gears.

Suitable means are provided for receiving and forwardly the sheets from the cutting mechanism and delivering them to the printing mechanism. In the embodied form, one or more sets of timing rollers or disks 30 and 31 are provided, having cut out portions 32 and 33 respectively for timing and effecting the release of the sheets whereby they will be properly taken by the grippers of the press. The rollers or disks 30 and 31 may be angularly adjustable for timing the different sheets, and as stated a plurality of sets of these rollers may be utilized. The feed rolls 13 and the timing rollers 30, 31 have the same surface speed as the web, and they may have gear connections to the web feeding rolls 2 and 3 for this purpose, so that their speed may vary with that of the web. Preferably the rolls 2, 3, 13, 30 and 31 are the same in size. Suitable guide bars or other auxiliary devices may be employed for directing and forwarding the sheets, but are not shown in the drawings.

The embodied form of printing means comprises a rotary perfecting press. The cylinder 40 being the first form cylinder, the inking devices therefor being indicated generally by reference numeral 41. The coöperating impression cylinder 42 is provided with two sets of grippers 43 and 44, each set of grippers being adapted to take a sheet upon each revolution of the cylinder and to hold it while being imprinted by the form cylinder 40 and then to deliver the sheet to the second printing couple.

The second printing couple comprises a form cylinder 45 having inking mechanism indicated generally as 46. The second impression cylinder 47 has two sets of grippers 48 and 49 respectively, spaced a semi-circumference apart. Said sets of grippers 48 and 49 are adapted to take each a sheet from the grippers 43 and 44 of cylinder 42 upon each

rotation of the cylinder 47, and to hold the sheets while being printed upon by the form cylinder 45, the sheet thereby being printed upon its second side or perfected, the perfected sheets then being delivered to the folding mechanism. Referring more fully to the operation of the mechanism already described:—

The web may be fed at the speed of the press cylinders, the cutters in such case using one pair of knives, and cutting twice for each revolution of the printing cylinders. The grippers 43 and 44 on the printing cylinder take successive sheets. If the speed of the web be lessened with the printing cylinders and the sheet cutter continuing at the same speed, two sheets will be delivered to the grippers 43 and 44, but they will be shorter than when the web was running at full speed, and will be proportionately shorter as the speed of the web is lessened. Such slowing down of the web may be considerable without interfering with the successful cutting of the web, and the sheets fed to the press will be correspondingly shortened. The timing devices will be arranged to insure the proper and timely delivery of the sheet irrespective of its change in size.

When the cutters are run at half the surface speed of the press cylinders, they are equipped with two pairs of cutters and are thus running within practicable limits to the speed of the web and yet are able to deliver a sheet each time to each gripper 43 and 44 on the printing cylinder. The web may be run somewhat faster than half speed and thus will deliver sheets somewhat longer than half the full sheet length owing to the web running faster than the cutters. The web speed may be slackened and thus gradually lessen the length of the sheet, cut therefrom and delivered to the press. When the web is running at the same speed with the slow running cutters the sheet delivered is practically half the length of the full sheet. The web may be further slowed down below the speed of the slow running cutters and the length of the sheets correspondingly shortened. The speed and position or adjustment of the timing disks will be accordingly regulated, so that notwithstanding variations in the length of the sheets, they will be properly delivered to the grippers. Thus the length of sheet fed to the press may be graduated by small and numerous decrements or increments between the longest size which the impression cylinder will take and a sheet considerably shorter than half size, and at the same time a sheet of any of these various and numerous sizes is delivered each time to each sheet taking gripper 43 and 44 of the impression cylinder. Thus the one mechanism is capable of printing all the various sizes.

Folding means are provided adapted to

fold the various sized printed sheets delivered from the press, and in accordance with certain features of the invention such folding mechanism is adapted to fold the printed sheets a plurality of times in succession. In accordance with certain features of the invention, the folding means of the kind described are also rotary. The folding mechanism is adapted to take the printed sheets from the impression cylinder 47, and in the embodied form said sheets are taken by a folding cylinder 50, either a solid cylinder or a series of disks, or of other suitable form. The cylinder 50 is provided with a set of grippers 51 adapted to take the lead end of the sheet from the grippers 48 and 49 of impression cylinder 47. The folding cylinder 50 is preferably half the size of the impression cylinder 47 and rotates two to one with respect thereto. The cylinder 50, in accordance with certain features of the invention is also a collecting cylinder. In such case grippers 51 are adapted to take one sheet from cylinder 47 and then another sheet on top the first one, the two sheets being folded off together. Any suitable form of operating and timing means for grippers 51 may be used, various devices for this purpose being well-known.

The folding cylinder 50 or other like carrier, is provided with a folding blade of any suitable or approved construction and manner of operation, the said folding blade 53 being angularly adjustable about the shaft 52 of cylinder 50 to bring the folding blade 53 in position to make a middle fold in all the different sizes of sheets held by the gripper 51. For this purpose the folding blade 53 is mounted upon arms 54, conveniently carried at either end of the cylinder 50, the arms 54 being mounted upon the shaft 52 of the cylinder 50 and being angularly adjustable relatively to said shaft and being held in adjusted position by suitable means, such as clamping screws 55. The cylinder 50 may be cut away as shown at 56 to permit the angular adjustment of the folding blade 53 and to provide suitable means, where necessary, for operating the folding blade in case a movable folding blade be used.

The embodied form of means for coöperating with the folding blade 53 to fold the sheet upon the cylinder 50 and to receive the folded off sheets, comprises a cylinder, or like carrier 60, mounted on a shaft 61. Said cylinder 60 is provided with a folding jaw or jaws 62 of suitable or approved construction for coöperating with the folding blade 53 to nip or fold the middle of the sheet or sheets upon the cylinder 50 and to carry them away therefrom by the fold. The detail mechanism for operating the folding jaw 62 is not shown herein, and any convenient form of operating means may be

provided so far as concerns most features of the invention. The folding blade 53 and coöperating folding jaws 62 will be timed to fold every sheet or every two sheets off from the cylinder 50.

The cylinder 60 is angularly adjustable upon the shaft 61 to bring the folding jaw or jaws 62 into operative relation with the folding blade 53, when the folding blade is angularly moved to fold sheets of different sizes delivered to the cylinder 50 from the impression cylinder 47. So far as concerns many features of the invention, the entire cylinder 60 need not be angularly adjustable, but a supporting portion for the gripper jaws 52 might be adjustable by itself.

The cylinder or like member 60, in the present embodiment, is provided with a folding blade 63 carried upon arms 64 at either end of the cylinder 60, said arms being adjustable upon the shaft 61 of the cylinder 60. The folding blade 63 is adjustable so as to give a fold or tuck medially to the sheet held by its fold by the gripper 62 to effect the second fold in the sheet in co-operation with suitable folding jaws. The cylinder 60 is cut away at 65 to permit the angular positioning of the blade 63, and suitable means, such as clamping screws 66 are provided for holding the arms 64 in position upon the shaft 61. The folding jaws 67, which coöperate with the blade 63 are carried upon a cylinder 68 or like member, the folding operation being substantially the same as that already described, as when the second fold is made in the sheet, the folding jaws 62 release the first folded edge, the releasing mechanism not being shown but same may be of any known and suitable form.

Means for giving one additional fold are shown in the embodied form, and may be generally similar to those already described and need not be further described in detail. The angularly adjustable folding blade 69 is in the same relation to the gripping jaws 67 as the folding blade 53 is to the folding jaw 62 and may be variously positioned to medially fold the folded shape as held by the folding jaws 67. Folding jaws 70 are carried upon a cylinder or like member 71, this cylinder 71 acts also as a delivery cylinder, the jaws 70 releasing the product to a receiving belt or cable 72, the stripper 73 being used, if desired, to insure the delivery of the folded sheet onto the table 72.

The manner of operation of the mechanism just described is substantially as follows:—

The sheet taken by the gripper 43 on cylinder 42, or that taken by the gripper 44 as may be, is carried through the first impression between cylinders 40 and 42 and is then delivered to either the grippers 48 or 49 upon the cylinder 47 and carried through

the second impression between that cylinder and form cylinder 45. The perfected sheets are then delivered, either singly or successively in twos, by the grippers 48 or 49 to 5 the grippers 51 on cylinder 50, the sheet thus being transferred to cylinder 50. The folding blade 53 and folding jaws 62 make the first fold in the sheet, which is at the same time released by the grippers 51 and 10 carried away, held upon cylinder 60 by the folding jaws 62. Folding blade 63 and folding jaws 67 make the second fold in the sheet, and simultaneously the gripping jaws 62 release the first folded edge, the sheet 15 then being carried around upon the cylinder 68, held by the fold in jaws 70 make another fold in the sheet, which is simultaneously released by the folding jaw 67. The folding jaws 70 carry the sheet around cylinder 20 71 and the sheet is then released and deposited upon the delivery device 72.

Means are provided by the invention for running the web through the printing machine uncut, when desired, and cutting and 25 folding subsequent to the perfecting of the web. In this way a full length sheet is run through the machine, that is, a sheet of the full length of the semi-circumference of the printing cylinders.

30 For this purpose, there is provided at a point in the machine subsequent to the printing cylinders 40 and 42 and 45 and 47 cutting devices 80 and 81. Said cutting devices are provided with cutting blades 82 and 83. The perfected web is led thereto from the last printing couple 45, 47 over guide rollers 84, 85 and 86, with suitable tension rollers, such as the roller 87. Below the cutting mechanism 80 and 81 are arranged feeding and timing rolls 88 and 89, which direct the cut sheets into a pathway formed by suitable means, such as two series of inclined guide bars 90 and 91, which direct the sheets into the gripper 51 upon 45 the cylinder 50, the folding taking place as before.

In doing high class work, such as magazine and fine pamphlet work, when perfecting the web, offset devices are employed in 50 connection with the second printing couple to prevent blurring, smearing or other impairment or defacement of the fresh impression made on one side of the sheet by the first printing couple. In the embodied 55 form of such means, an offset web 92 is run from a supply reel 93 around impression cylinder 47, between said cylinder and the fresh printed web, said offset web being rewound upon a roll 94. Means are provided for 60 preventing the offset sheets from soiling the surface of the cylinder 47, and for this purpose an oil wiping mechanism 95 is provided operating upon the surface of the impression cylinder 47.

65 When running the web, if desired, the

forms may extend completely around the form cylinders, and the sheets may be full half length of the impression cylinder and the grippers may be retracted and a filler piece used in a well known manner. Thus 70 the very largest size sheets may be run and cut off after the printing on both sides.

From all the foregoing it will be understood that a machine has been provided embodying the principles of the invention and 75 realizing the objects and advantages set forth, together with other objects and advantages.

The invention in its broader aspects is not limited to the illustrated and described 80 form, but changes may be made therein without departing from the principles of the invention and without sacrificing its chief advantages.

I claim—

35 1. A printing machine including in combination printing cylinders, paper supplying means comprising a variable size sheet supplying mechanism for feeding to said cylinders and means for cutting a web after 90 it has been printed by said cylinders, and folding means adapted to receive sheets direct from the printing cylinders or from said means for cutting the printed web.

2. A printing machine including in combination printing cylinders, paper supplying means comprising a sheet supplying mechanism for feeding to said cylinders and means for cutting a web after it has been 95 printed by said cylinders, and folding means 100 adapted to receive sheets direct from the printing cylinders or from said means for cutting the printing web.

3. A printing machine including in combination two web cutting mechanisms, one 105 for cutting the unprinted web and the other for cutting the printed web, printing cylinders interposed therebetween and folding means adapted to receive the sheets either directly or indirectly from the printing cylinders. 110

4. A printing press including in combination two web cutting mechanisms, printing cylinders interposed therebetween and adapted 115 to receive the web from one cutting mechanism or to deliver it to the other, and folding means adapted to receive the sheets either directly from the printing cylinders or from the last mentioned web cutting mechanism.

5. A printing press including in combination printing means adapted to print upon sheets of different sizes or upon a web alternatively operable sheet producing mechanisms comprising means for cutting sheets 125 of various sizes and supplying them to the printing mechanism and means for cutting the web into sheets after it has been printed by the printing mechanism, and folding means adjustable for all the various sizes of 130

sheets and taking the printed sheets either directly from the printing mechanism or from the cutting means for the printed web.

6. A printing press including in combination printing means adapted to print upon sheets of different sizes or upon a web, alternatively operable sheet producing mechanisms comprising means for cutting sheets of various sizes and supplying them to the printing mechanism and means for cutting the web into sheets after it has been printed by the printing mechanism and rotary folding means adjustable for all the various sized sheets and taking the printed sheets either directly from the printing mechanism or from the cutting means for the printed web.

7. A printing press including in combination rotary printing means adapted to print upon sheets of different sizes or upon a web, alternatively operable sheet producing mechanisms comprising means for cutting sheets of various sizes and supplying them to the printing mechanism and means for cutting the web into sheets after it has been printed by the printing mechanism and rotary folding means adjustable for all the various sizes of sheets taking the printed sheets either directly from the printing

mechanism or from the cutting means for 30 the printed web.

8. A printing press adapted to print upon vari-sized sheets or upon a web, including in combination variable speed web feeding means, printing means having silenceable 35 sheet-taking devices, means for supplying thereto sheets of full length from said web, half length, or length varying from either, and folding means adapted to centrally fold the printed sheets of all the different sizes. 40

9. A printing machine including in combination a rotary printing couple, variable speed web feeding means, all size cutters supplying sheets thereto from said web, fixed size cutters cutting a printed web coming 45 from the printing couple, and a common folder for receiving the sheets directly from the printing couple or from the fixed size cutter when the couple is printing on the web, and having means for folding all sizes 50 of either sheets centrally transversely.

In testimony whereof, I have signed my name to this specification, in the presence of two subscribing witnesses.

RALPH C. SEYMOUR.
